UNITED STATES PATENT OFFICE

122,355

DESIGN FOR AN EMBROIDERED FABRIC OR SIMILAR ARTICLE

Joseph Hartmann, Garfield, N. J.

Application August 2, 1940, Serial No. 94,165

Term of patent 3½ years

To all whom it may concern:

Be it known that I, Joseph Hartmann, a citizen of the United States, residing in the city of Garfield, county of Bergen, and State of New Jersey, have invented a new, original, and ornamental Design for an Embroidered Fabric or Similar Article, of which the following is a specification, reference being had to the accompanying drawing forming a part thereof.

The figure of the drawing is a plan view of an embroidered fabric or similar article, showing my new design.

The ridges and figures appearing in the drawing are raised above the surface of the fabric, the design as a whole having a raised and puffed appearance.

I claim:

The ornamental design for an embroidered fabric or similar article, as shown and described.

JOSEPH HARTMANN.
